UNITED STATES PATENT OFFICE

2,657,653

SEWING MACHINE

Clyde L. Knott, Beverly, Mass., assignor to United
Shoe Machinery Corporation, Flemington,
N. J., a corporation of New Jersey

Application February 10, 1950, Serial No. 143,536

39 Claims. (Cl. 112—36)

1

The present invention relates to machines for sewing shoes or other articles composed of stiff heavy materials with a lock stitch seam, and more particularly to improvements in the type of machine employing a straight hook needle to enable speeds of operation higher than obtainable with previous similar machines. In certain aspects, the invention is of more general application to machines including that type employing curved needles, whether intended for inserting a lock or a chain stitch seam.

Shoe sewing machines of the hook needle type ordinarily are somewhat more heavily constructed than those of the eye-needle type and, consequently, the actuating devices of such machines have greater inertia and cannot be operated efficiently at relatively high sewing speeds. For this reason, and because shoes or other parts intended to be operated upon are composed of heavier materials than those operated upon by machines of the eye needle type, no attempt has been made heretofore to construct a hook needle machine intended for operation at speeds greater than a thousand sewing cycles per minute. Ordinarily practical speeds for hook needle machine operation are far below this figure.

It is an object of the present invention to provide a hook needle shoe sewing machine of improved construction and advantageous mode of operation in which relatively heavy parts are employed, as compared with the parts of an eye needle sewing machine, but which is capable of practical operation at speeds in excess of a thousand stitch forming cycles per minute without the difficulties encountered in high speed operation of similar prior machines. A further object of the invention is to provide a sewing machine of the type referred to which will have greater durability, a higher quality of work performance and a smaller requirement for skill or effort on the part of the operator of the machine.

One difficulty frequently encountered in the operation of any high speed shoe sewing machine is in imparting a uniform feeding movement to the work operated upon without exerting on the work such heavy clamping pressure as to injure the surface or to flatten the work to a degree where permanent distortion occurs. Accordingly, one feature of the invention resides in the use of a relatively stationary guide foot against which the work is held, and in a work support movable toward the guide foot to clamp the work, a feed foot being connected to the work support by a floating actuating lever to cause the work support to be lowered positively from

2

engagement with the work during the feeding movement of the feed foot. This arrangement differs from the usual one in which the work support comprises a fixed clamping member and the feed foot only moves to clamp the work. The work is held in the usual machine against the work support at all times and is guided by engagement therewith. During normal operation of such prior machine, the tendency is to force the work so firmly against the work support that freedom for full unrestricted feeding movement of the work is substantially impaired. Accordingly, variation in stitch length results. By the use of a feed foot actuated through a floating lever connected to the work support, the work support is disengaged from the work during feeding movement by the resistance offered to the clamping pressure of the feed foot. Consequently, the grip of the feed foot on the work may be made much lighter than in a machine having a fixed work support. Preferably, a pair of feed feet is employed, acting at both sides of the work, both feet being actuated simultaneously to clamp and feed the work.

Another feature of the invention which enables higher sewing speeds, particularly in the use of a hook needle and an awl, is that embodied in a rotary needle looper arranged with its axis in alignment with the awl and provided with an awl guiding opening into which the needle enters during the looping operation. This feature consists in providing a thread measuring finger mounted for rotation about an axis at an angle to the rotating axis of the looper. In one form of this feature a member cooperates with the thread finger to insure that a uniform length of thread will be measured. As hereinafter illustrated, the thread finger is provided with an arcuate thread engaging flange and a concave member within the concavity of which the thread finger traps thread between the concave member and itself during the thread measuring operation.

Other features including a novel and improved loop picker assist in transferring each loop of thread from the needle to the shuttle, and as hereinafter described and claimed will be apparent from the following detailed description and accompanying drawings, in which

Fig. 24 is a similar view in right side elevation of some of the connections and mechanism illustrated in Fig. 23 but displaced in relation to each other from that assumed during normal operation;

Fig. 25 is a time chart of certain parts includ-

ing the principal stitch forming devices and feed feet in the machine; and

Fig. 26 is a perspective view on a somewhat reduced scale of the thread finger actuating mechanism.

The illustrated machine is a lock stitch shoe sewing machine intended for operation upon relatively heavy stiff materials including sole members to insert a seam at speeds higher than employed in present day practice for corresponding machines. The illustrated machine is capable of operation at approximately 1500 stitches per minute as compared with 700 to 800 stitches per minute maximum for similar machines in present day usage. In the attainment of this speed all the principal actuating mechanisms for the stitch forming and work feeding devices are camless and are driven through crank and pitman connections with the main sewing shaft to assist in obtaining the proper timing of the stitch forming and other actuated devices. Rotating varying speed-ratio drives are employed with certain of the mechanisms to insure smooth operation.

Referring more particularly to the drawings, the stitch forming devices of the machine include a work penetrating straight hook needle 2 operating below the work, a work penetrating straight awl 4 at the opposite side of the work, a shuttle or loop take 6 at the same side of the work with the needle, a rotary needle looper 8, a thread measuring finger 10 acting on the needle thread stretched between the needle looper and the work, a pointed loop picker 12, a take-up 14, and a combined thread tension and lock 16. The formation of a seam by the stitch forming devices is generally similar to that in prior machines, the work being clamped during stitch formation between a stationary guide foot 18 and a yieldingly actuated work support 20.

It is the usual practice in the design of straight needle sewing machines, particularly those intended for operation on stiff heavy materials, to provide a stationary work support and to enable the work to be clamped in fixed position by movement toward and from the work support of a movable presser foot. In presenting the work to the machine and in changing its position as the operation progresses, the operator presses the work downwardly against the work support causing a frictional drag to be exerted on the work by the work support and imposing an obstacle to uniform feeding action of the machine.

In the machine of the present invention, the frictional drag of the work on the work support during feeding movement is in large degree overcome, the work support being raised yieldingly against the work and being moved positively downwardly away from the work during each feeding movement, and the work being maintained in suspension momentarily during feed between the work support and guide foot 18. To impart downward movement of the work support away from the work during work feed, the work support has connected to it a feed foot 22, through a floating actuating lever 24 of elbow form (see Fig. 5). The floating lever is fulcrumed on a stub-shaft 25 mounted in the work support. To counteract the upward pressure of the feed foot and to stabilize the position of the work in suspension between the work support and guide foot, there is provided a second feed foot 26 at the upper side of the work acting in a similar manner but in an opposite direction disengaging the work from the guide foot. Thus,

the weight of the work and the downward pressure exerted on the work by the operator cause no undesirable frictional drag on the work support and as a result a lighter clamping action of the pair of feed feet 22, 26 can be used than otherwise would be necessary.

The work support is movable toward and from the guide foot by reason of its mounting in a vertical guideway 28 (see Figs. 2 and 5), formed by a pair of parallel grooved plates 30, secured to the outside surface at the forward part of a hollow enclosing frame 32 by machine screws 34. The side edges of the work support are formed with parallel ferrules 36, entering the grooves of the plates 30. The work support is in the form of a shell with a tapering upper work engaging end perforated and slotted to receive the needle and the feed foot 22.

To raise the work support yieldingly and maintain it in clamping engagement with the work against the thrust of the awl, the work support has surrounding a sleeve portion 37 thereon the upper end of a link 38, the lower end of which is pivotally connected to an arm 40 secured to a shaft 42 rotatably mounted in the machine frame 32. The shaft 42 extends rearwardly of the machine and has fixed to its rearward end a vertical arm 44 (see Fig. 4) pivotally connected to a bar 46. The bar 46 has a shoulder engaged by a coil compression spring 48, and is slidably mounted in a tubular bushing 50 threaded in the right side wall of the machine frame. The inner end of the bushing acts against the spring 48 to enable the compression of the spring to be varied and the upward pressure of the work support on the work to be increased or decreased. To limit the upward movement of the work support when no work is presented to the machine, the vertical arm 44 engages a stop pin 52 projecting inwardly from the machine frame.

Referring further and more particularly to Fig. 5, the upper feed foot 26 is pivotally mounted at 54 on an elbow actuating lever 56. The lever 56 is fulcrumed on a stub shaft 58 secured in the frame 32 of the machine.

In feeding the work the feed feet 22, 26 engage and clamp the work at the forward side of the seam line and move from right to left a stitch length while in engagement with the work. To this end the elbow levers 24, 56 for actuating the feed feet against the work are given equal rocking movements about their respective fulcrum shafts 25 and 58.

The mechanisms for actuating the elbow levers to clamp and release the work are similar to each other and are connected for vertical sliding movement to the longer arms of the levers. These mechanisms comprise diametrically slotted pins 60 and 62 surrounding at their slotted ends the reduced ends of the levers, the pins being rotatably mounted in arms 64 and 66, respectively, secured to the forward ends of a pair of horizontal shafts 68 and 70. The shafts 68 and 70 are rotatably mounted in the machine frame and have their rearward ends fixed to arms 72 and 74 extending relatively in opposite directions from their respective shafts. The free ends of the arms 72 and 74 are connected to a pair of pitmans 76 and 78 engaging separate cranks 80 and 82 of equal throw disposed 180° apart on a shaft 84 comprising the main sewing shaft of the machine. The arrangement is such that in clamping the work the pressure exerted by the feed foot 22 causes the work support 20 to be forced downwardly in its guideway 28 and in moving down-

wardly the lower end of the elbow lever 24 slides vertically in the slot of the pin 60 without disturbing the movements of the parts.

To impart feeding movements to the feed feet 22, 26 the lower end of the feed foot 22 and the upper end of the feed foot 26 are connected by horizontal links 86 and 88 to upwardly projecting arms 90 and 92, respectively secured to the forward ends of a pair of horizontal shafts 94 and 96. The shafts 94 and 96 have secured to their respective rearward ends a pair of arms 98 and 100 connected in turn through a pair of links 102 and 104 to opposite ends of a single vertical lever 106 rotatable at a central point along its length on a fixed shaft 108. The shaft 96 is rotatable in fixed bearings and the shaft 94 is rotatably mounted in a bearing carried by the work support. The bearing for the shaft 94 comprises the sleeve portion 37 of the work support 20 and moves vertically with the work support. However, the horizontal link 102 swings slightly during vertical movement of the shaft 94 without affecting its angular position. The hub of the arm 98 abuts the link 38 and holds it from axial displacement from the sleeve portion 37 of the work support 20, as best shown in Fig. 3.

Since the ends of the vertical lever 106 move in opposite directions a motion reversing connection is necessary between the connecting lever and one of the feed feet. In order to cause the feed feet to move along the line of feed in the same direction, the arm 92 projects upwardly from the shaft 96 and the arm 100 projects downwardly, and the arms 90 and 98 on the shaft 94 for the lower feed foot both project upwardly. Thus, the arm 92 moves in the same direction as the arm 90 and reverses the motion produced by the ends of the vertical actuating lever 106.

To provide convenient means for varying the feeding movements of the feed feet, an adjustable throw connection is included in the feed foot actuating mechanisms. The adjustable throw connection comprises a pair of toggle links 110 and 112 pivotally connected between the lower end of the vertical lever 106 and a forked arm 114 secured to an adjusting shaft 116 rotatable in the machine frame. The adjusting shaft 116 also has fastened to it a gear segment 118 meshing with a worm 120 integral with a shaft 122. The shaft 122 is rotatable in a flanged bearing 124 (see Figs. 1 and 2) fastened to the right side wall of the machine frame 32, the worm 120 being disposed inside the frame. Outside the frame the shaft 122 has pinned to it a crank arm 126 (Figs. 1 and 2) within the crank portion of which is slidably mounted a spring pressed plunger 128 arranged to engage at its inner end selectively with one of a series of holes 130 in the flange of the bearing 124. Rotation of the crank through the connection described, changes the position of one end of the toggle links.

The central joint of the toggle links consists of a pin 132 at the outer ends of which is a pair of connecting links 134 (see Figs. 3 and 5). The links 134 connect the pin 132 with the arms of a yoke 136 through a pair of pins 138. The yoke 136 has fulcrum studs 140 projecting outwardly therefrom and rotating in bearings in the machine frame.

The yoke 136 is actuated to move the links 134 and the central joint pin 132 of the toggle links toward and from a position of alignment with the end pivots thereof to actuate the feed feet, through a forwardly projecting arm on the yoke.

connected to a pitman 142 driven by a crank 144 projecting from the hub of a gear 146. The gear 146 rotates loosely on a stud 148 fixed in the machine frame, the mechanism thus described comprising a direct acting train of connections between the crank 144 and the feed feet.

It is understood, in general, that the nature of any driving mechanism, not employing cams and followers or rolls for actuating devices in a machine of the type referred to, may be determined by considering separately the character of the main rotating member in the machine and the connections driven thereby. A convenient classification, particularly in the case of the present invention, assigns such members to either of two groups. One of these groups includes the use of a simple constant speed rotating crank or eccentric member. The other group includes a camless rotating varying speed-ratio drive, such for instance, as that employing planetary gear action or a drag-link.

In the connections driven by the main rotating members there also are two corresponding groups of linkages, one of the direct acting oscillating type in which the full stroke of a crank pitman or eccentric strap is employed to provide the full stroke of the device operated thereby. The other connection group is of the compound timing-changing type in which the operated device is caused to dwell or even has its motion reversed at an intermediate point in the stroke of a crank pitman or eccentric strap on the rotating member or drive. To obtain timing change, the usual practice is to provide a lever and link connection in which the pivots thereof are brought into substantial alinement or are carried past a position of alinement before the end of the stroke of the crank pitman or eccentric strap is reached.

In the illustrated machine, two rotating varying speed-ratio drives are employed generally similar to that disclosed in United States Letters Patent No. 2,309,595, granted January 26, 1943 upon application of Lester E. James.

A lower one of the rotating varying speed-ratio drives rotates the feed actuating gear 146 with its crank, a single rotation for each two rotations of the varying speed-ratio drive, in such a way that it imparts a rapid movement to the feed feet twice during each sewing cycle, once during feeding movement and once during back feeding movement thereof. Between the times of feeding movement, the movements of the feed feet and the actuating connections are relatively slow at which time formation and tightening of each stitch is being accomplished.

The lower rotating varying speed-ratio drive for the gear 146 includes a tubular variable speed shaft 150 having a spur gear 152 secured thereto, as shown in Figs. 3 and 5, meshing with the teeth on the gear 146. The shaft 150 together with a pinion 154 thereon comprises the driven member of the varying speed-ratio drive. For rotating the pinion 154 its teeth engage those of a gear toothed segment 156 pivotally mounted at 158 for oscillation near the outer edge of a flanged disc 160. Except for movement of the segment about its pivot 158 the pinion 154 and shaft 150 would be rotated in unison with the disc. However, the segment 156 has loosely secured therein a pin 162 forming a connection with one end of an eccentric strap 164 surrounding a stationary eccentric 156, which during rotation of the disc 160 causes the segment to oscillate about its pivot 158 relatively to the disc. In so doing, the pinion 154

has imparted to it a rotation of varying speed-ratio.

The disc 160 is rotated twice during each sewing cycle so that it imparts two relatively quick and two relatively slow movements to the pinion 154 during each sewing cycle. The gear 152 has one-half the number of teeth as those on the gear 146 so that only a single feeding movement is imparted to the feed feet during each sewing cycle, the arrangement being such that a quick movement occurs during actual feeding movement. Another quick movement occurs during the back feeding movement of the feed feet so that the back feeding movement is not prolonged sufficiently to interfere with the stitch forming operations.

To drive the disc 160 of the lower varying speed ratio drive two revolutions for each single rotation of the sewing shaft, the disc has secured to its rearward side of a spur gear 168 having half the number of teeth as a driving gear 170 therefor on the main sewing shaft 84. The driving gear 170 is mounted for convenient removal from the sewing shaft both for purposes of assembly and accessibility to the parts in the machine, as well as to enable convenient timing adjustments to be made. For these purposes, the gear has an elongated hub and a flat collar portion at its rearward side engaging a shoulder 172 on the main sewing shaft. The hub of the gear has an opening to receive the shaft and is clamped to the shaft by a conical nut 174 secured in clamped position by a multi-finger washer 176. In clamping the gear 170 against the collar 172 pressure is exerted upon an anti-friction bearing 178 on the sewing shaft to retain it in place within an opening 180 in the machine frame, the bearing forming a support for the forward end of the sewing shaft. The support for the rearward end of the sewing shaft is best shown in Fig. 4 and is similar to the bearing 178. The rearward support consists of an anti-friction bearing 182 clamped to the shaft by a nut 184 locked in place by a multi-finger washer 186. The bearing 182 also is clamped against axial movement in the machine frame between a flanged sleeve 188 rigid with the frame and a clamping ring 190 secured to the flange of the sleeve. The sleeve 188 in turn has an internal shoulder against which the bearing is clamped by the ring 190.

Besides operating the feed feet along the line of feed, the lower varying speed ratio drive 150-160 also serves to rotate the shuttle 6 twice during each sewing cycle with a rapid rotating motion during the time the shuttle is receiving each loop of needle thread, indicated at 191, and with a dwell in its movement while each needle loop is being shed from the shuttle. For these purposes, the shaft 150 has at its forward end a bevel gear 192 meshing with a corresponding gear 194 on the underside of the shuttle. The gear 194 and the shuttle are mounted to rotate on a vertical axis comprising a hollow vertical shaft 196 secured in the machine frame at an angle of ninety degrees to the plane of the work operated upon and entering a suitable bearing opening within the gear 194 and the shuttle.

The shuttle is of conventional loop-taker form with a beak 198 (see Fig. 13) and an internal raceway to receive a projecting radial flange 200 (Fig. 8) of a discoidal thread case 202 held from rotation with the shuttle and arranged to receive a supply of locking thread 203 within it. To retain the thread case from rotation with the

shuttle an upwardly projecting hollow arm 204 of the machine frame has at its upper end a notch 206 within which is loosely disposed a forwardly projecting lug 208 formed integrally with the thread case. As each loop of needle thread 191 is carried about the thread case by the shuttle, it is drawn upwardly into the notch 206 and eventually is carried through the space between the lug and the notch. The shuttle is held stationary while the loop is carried between the lug and the notch, thus avoiding pressure of the lug on one side of the notch and facilitating release of the loop. The thread case also has a locking thread tension 210 comprising a circular spring strip disposed within a circumferential groove in the side wall of the thread case.

The hook needle 2 is clamped to the upper end of a reciprocating needle bar 212 slidingly mounted in bearing sleeves 214 and 216 in the machine frame (see Fig. 3), with its open hook facing against the direction of work feed. In order to give the necessary dwells and rapid movements required while looping the needle and while transferring the needle loop to the shuttle the needle bar is actuated by mechanisms including one of the constant speed type driven by the main sewing shaft and link motion connections of the compound timing-changing type.

To provide simple and effective means for assisting in transfer of the needle loop from the needle to the shuttle, the loop picker 12 has its free loop entering end pointed in the same direction as the beak 198 of the shuttle. The loop entering end of the picker which cooperates with the needle to disengage the loop from the needle and to hold one side of the loop in the path of the shuttle beak is thus pointed against the direction of work feed, the shuttle beak being pointed similarly. The picker 12 also is actuated by compound timing-changing connections including a part of the needle actuating link motion.

The needle and picker actuating mechanism is driven from the main sewing shaft 84 through the constant speed crank 80 at the forward end of the sewing shaft just behind the forward main bearing 178, as best shown in Fig. 3.

Referring also to Figs. 6 and 7, the crank 80 is surrounded by a bearing of a pitman 218 having its outer end pivotally connected at 220 with the upper arm of an angle lever 222 fulcrumed loosely on a shaft 223 secured in the machine frame by a draw bolt 224. The shaft 223 forms a support about which the driving disc 160 rotates. The mid-portion of the shaft 223 also has secured it to the eccentric 166 for the feed actuating varying speed ratio drive and the forward end of the shaft 223 is reduced in diameter to provide a spindle about which the tubular shaft 150 rotates. The lower arm of the lever 222 has two forks, one of which is pivotally connected at 225 with a link 226, in turn connected to the shorter rearward arm of a forked lever 228 including a shaft 230 to which the lever 228 is secured, rotatably mounted in the machine frame. The forward arm of the lever 228 being at the front of the machine (see Fig. 3) is connected through a link 232 with a pin 234 projecting from a block 236 clamped to the needle bar 212. In the needle actuating mechanism the lower arm of the lever 222 and the link 226 have their pivots brought into substantial alignment and are carried past alignment to cause the timing in the stroke of the needle to differ from that of the pitman 218 and also the forward arm of lever 228

and link 232 produce a still further change in timing.

For actuating the loop picker 12 the pivot 225 has surrounding it loosely at its forward end one end of a link 238 connected at its other end with a forked bell crank 240 rotating loosely on the shaft 230. The bell crank 240 also is pivotally connected to a link 242, in turn connected to a bell crank 244 including a horizontal shaft 246, the forward arm of which bell crank is connected through a link 248 to a pin 250 carried by a lug on the picker 12. The picker 12 is in the form of an oscillating arm mounted on a stud 252 secured in the machine frame along the line of the seam inserted by the stitch forming devices beyond the needle.

A feature of the illustrated machine contributing effectively to smooth accurate operation at relatively high speed comprises the arrangement of the awl and needle looper. The awl 4 is somewhat longer than required for the thickness of work intended to be operated upon by the machine and is secured to the lower end of a reciprocating bar 254 within spaced bearing sleeves 256 (see Fig. 3) secured in an overhanging portion of the machine frame and in vertical alignment with the bearings 214 and 216 for the needle bar.

To guide the awl and to prevent deflection, the lower end of the awl passes through an axial opening 257 in a spindle at the side of the work opposite the shuttle, comprising the needle looper 8 rotatably mounted in bearings 258 also in alignment with the needle and awl bar bearings, the needle also entering the axial opening during the looping operation. The opening 257 is concentric with the axis of looper rotation so that rotation of the looper spindle does not interfere with the reciprocation of the awl but does insure working engagement and penetration by the awl with certainty at the desired location.

The awl actuating mechanism is driven from the main sewing shaft 84 through an upper rotating varying speed ratio drive connected through a compound timing-changing linkage.

The upper varying speed ratio drive for the awl mechanism consists of a flanged disc 260 (see Figs. 3, 6 and 7) having gear teeth meshing with the driving gear 170 on the main sewing shaft 84 and in turn rotatably mounted on the mid-portion of a shaft 262 secured by a drawbolt 264 in the machine frame in parallel relation to and above the main sewing shaft 84. As in the case of the flanged disc 160, the disc 260 has mounted for rotation therein a pivot 266 to which is secured a gear toothed segment 268 arranged for oscillation with the pivot. The teeth of the segment 268 mesh with those of a pinion 270 rotatable on the reduced forward end of the shaft 262. The hub of the pinion projects through an opening formed in a vertical removable partition 272 in the frame of the machine, the partition holding the pinion against displacement from the shaft 262. To the hub of the pinion 270 at the forward side of the partition 272 is secured a crank arm 274 having a crank pin 276 to impart a varying speed drive for the link connections. The segment 268 is oscillated about the axis of its pivot 266 by a pin 278 (see Fig. 7) on the segment, forming a connection with one end of a strap 280 surrounding a stationary eccentric 282. The eccentric 282 is secured to the shaft 262 which projects through the flanged disc 260 of the varying speed ratio drive.

The compound timing-changing connections

11

for the awl actuating mechanism comprise a pitman 284 surrounding at one end the crank pin 276 and at the other end a pin 286 on an axially elongated bell crank 288. The bell crank 288 has a sleeve portion rotatably mounted on a fixed pin 290 secured at its ends in a lug on the partition 272 and in a forwardly disposed web of the machine frame, respectively. The forward arm of the bell crank 288 carries a pivot joint beyond the pitman 284 comprising an integral pin 292 surrounded by one end of a link 294 connected in turn by a pin 296 projecting from a block 298 clamped to the awl bar 254. The forward arm of the bell crank 288 and the link 294 have their pivot joint brought into substantial alinement with the pins 290 and 296 as illustrated in Fig. 7 to cause the motion of the awl to be reversed slightly during continued movement of the pitman 284 in one direction and to cause a more rapid penetrating and retracting movement of the awl than would be produced otherwise by the pitman. The effect of the reversal is slight in this instance, however, causing, in effect, a dwell in the movement of the awl while disengaged from the work.

The needle looper 8 is actuated by a mechanism best shown in Figs. 3 and 19 to 22, inclusive. This mechanism comprises gear teeth 300 on the looper spindle, engaged by teeth on a gear segment forming a part of a lever 302 fulcrumed on a vertical pin 304 secured at its upper and lower ends in the frame of the machine. A rearwardly extending arm of the lever 302 is forked and has secured between the forked portions a pin 306, provided with a central spherical enlargement. Surrounding the enlargement of the pin 306 is a correspondingly shaped socket at one end of a link 308 having at its other end a corresponding socket surrounding the spherical head of a pin 310. The pin 310 is secured in a crank arm 312 fastened to the forward end of a rock-shaft 314 rotatable in a bearing portion 316 of the machine frame (see Fig. 4). At its rearward end, the rockshaft 314 is connected to an arm 318 connected in turn by a link 320 with one end of an arm 322 rotatable on a pin 324 secured in a lug on the machine frame by a drawbolt 326. Between the ends of the arm 322 is a laterally projecting lug carrying a pivot 328 connected to a pitman 330. The pitman 330 surrounds the crank 32 on the main sewing shaft 84.

Cooperating with the rotary needle looper in a novel manner, particularly advantageous in handling the needle thread accurately and at high sewing speeds, the thread measuring finger 10 is arranged to rotate on a horizontal axis disposed at an angle of 90° to the vertical rotary axis of the looper 8. To prevent the thread finger 10 from interfering with the needle, the finger is in the form of a disc member having along one portion of its edge an arcuate flange 332 (see Figs. 8 et seq.) which projects into the path of the thread carried by the looper at one side of the needle between the looper and the last formed stitch in the work. At one end of the flange 332 there is a thread receiving notch 333 and the flange tapers toward its other end, finally merging with the disc portion of the looper.

To insure accurate measurement of the needle thread 191 by the thread finger 10 and to trap and prevent displacement of the measured supply of thread until released, the flange 332 moves within a concavity cut within the stationary guide foot 18, the surface of the concavity being disposed in close proximity to the thread finger.

12

By reason of its close proximity the thread measuring finger moves along the surface so the thread is pressed against the concave surface of the guide foot. To trap the measured thread between the flange 332 and the guide foot so that there is no possibility of escape for the thread, the concave surface in the guide foot has along its edge a circular groove 334 providing clearance for the thread between the surface and the thread finger when the thread finger is in its thread measuring position, the groove being indicated in Figs. 10, 11 and 12 only.

The needle thread as it enters the machine passes through the tension and lock 16 over the take-up 14 through a guiding slot 336 in the machine frame (see Figs. 1 and 2) and through an eccentric thread guiding opening 338 in an enlargement on the looper spindle. The operation of the looper and thread measuring finger will be apparent from the illustrations of Figs. 8 to 14, inclusive, in which Fig. 8 shows the eccentric thread guiding opening 338 of the looper at the side of the looper axis of rotation with the previously formed stitch in the work. When the awl has penetrated the work, as in Fig. 9, the looper starts its rotation in the direction of the arrow in that figure in order to carry the thread guiding opening 338 to a position at one side of the needle and behind the axis of looper rotation and into the path of the flange 332 on the thread finger. When the opening 338 in the looper reaches a position at one side and behind the axis of looper rotation, the thread finger is actuated in the direction of work feed during oscillation in the direction of the arrow 339 in Fig. 10 to engage the needle thread 191 and to start a measurement thereof. During continued measuring movement of the thread finger rotation of the looper is reversed. The thread finger is actuated finally to the position of Fig. 11 and during reverse rotation of the looper in the direction of the arrow in that figure the thread is laid in the hook of the needle, the needle entering the awl guiding opening in the looper. As soon as the thread is laid in the hook of the needle the needle retracts, as shown in Fig. 12, and the thread finger is actuated in the opposite direction to release thread to the retracting needle. At the lower end of the needle stroke the thread finger is entirely disengaged from the thread and moves to the position shown in Fig. 13 where it remains until the stitch is completed and is being drawn from the shuttle. During these movements of the thread the work is fed a stitch length, as indicated by the arrow in preparation for the insertion of a new stitch. Fig. 14 illustrates the positions of the parts just before the thread is disengaged from the thread case and thread case retainer lug 266. At this time in the sewing cycle, the thread finger starts again to move toward the needle thread.

The operation of the loop picker in transferring the thread from the needle to the shuttle is clearly shown in Fig. 13, the loop of needle thread being completely disengaged from the needle before engagement with the shuttle and the open hook of the needle facing against the direction of work feed. To assist in this operation, the loop picker is pointed at its free end in the same direction as the loop taker beak and the feed of the work and is formed with a central opening within which the needle enters during transfer of the needle loop in a manner similar to that in the machine of United States Letters Patent No. 2,431,404 granted November 25, 1947 upon application of the present inventor.

70

75

The thread finger is actuated through a mechanism driven from the crank 80 on the main sewing shaft (see Figs. 3, 17 and 18). For this purpose, the crank 80 has surrounding it a pitman 340 connected by a pivot 342 supported at its ends by the sides of a bifurcated lever 344 fulcrumed on a shaft 346 in the frame of the machine. The lever 344 has one of its arms pivotally connected to a link 348, in turn connected to an arm 350 secured to a horizontal shaft 352 rotatable in the machine frame. At the forward end of the shaft 352 is a forked arm 354 pivotally connected to a link 356 which in turn is pivotally connected to an arm 358 secured to a shaft 360 rotatable in stationary bearings. The shaft 360 carries a gear segment 362, the teeth of which mesh with corresponding teeth on an incomplete pinion 364 fast to a thread finger shaft 366 rotatable along its central portion in a fixed bearing 368 (see Fig. 3) secured to the machine frame and at its rearward end in a bearing lug on the partition 272. The disc of the thread finger 10 is formed integrally with the shaft 366 and comprises an enlarged head on the shaft. It will be noted with reference to Figs. 17 and 18 that the uppermost arm of the lever 344 and the link 348 form a toggle which is moved past a position of alinement of its centers and the arm 354 and the link 356 form a second toggle both of which approach positions of alinement during operation of the machine giving an increased dwell in the motion of the thread finger and changing the timing of the thread finger to this extent from the oscillatory motion imparted by the crank 80 to the pitman 340.

The take-up 14 is illustrated in Figs. 3, 15 and 16 and comprises a forwardly curved arm formed integrally with a horizontal shaft 370 rotatable in the machine frame in the upper part thereof. The take-up arm is located at the front end of the shaft 370 and at its rearward end the shaft has secured to it a second arm 372 (see Fig. 4) provided at its outer end with an internally threaded portion. The threaded portion of the arm 372 receives within it a threaded shank of a forked block 374 having extending across its forked portion a pivot 376. The pivot 376 is surrounded by the upper end of a link 378 within the fork of the block 374 (see Fig. 4), the lower end of which link surrounds a pin 380 secured between the sides of a fork armed lever 382 mounted for oscillation on a fixed shaft 384. The lever 382 also is connected through its opposite arm to a link 386, in turn connected to a pin 388 on the outer end of a pitman 390 surrounding the crank 82. To modify the motion of the pitman 390 it is pivotally connected along its mid-portion with a radius arm 392 in turn rotatably mounted on a pin 394 secured in a lug on the frame of the machine by a clamp bolt 395, best shown in Fig. 4. The outer end portion of the pitman 390 and the arm 392 form a compound toggle with the link 386 to provide a substantial timing-changing action with reference to the rotary movement of the crank 82, providing a desirable movement in the take-up 14.

The combined thread tension and lock is operated during each sewing cycle to increase and decrease the tension on the thread so that the thread may be handled properly by the stitch forming devices during stitch formation and so that each stitch may be set tightly and at a uniform depth within the substance of the work after stitch formation. The thread tension and lock consists of a pair of perforated discs 396

(see Figs. 1, 2, 3, and 23) between which the thread passes and through which extends a lengthwise sliding lock actuating shaft 398 passing horizontally through an opening into the machine frame. The rearmost disc 396 is pressed against the machine frame and the forward disc is pressed against the thread by a spring 400 coiled about the shaft 398. The spring 400 acts between the outer disc and a thumb nut 402 threaded on the outer end of the shaft. At the rearward end of the shaft 398 it is surrounded by a coil spring 404 (Fig. 3) stronger than the spring 400 at the forward end of the shaft. When allowed to expand, the spring 404 compresses the spring 400 and locks the thread with a heavy pressure. The rearward end of the shaft is threaded and carries a pair of check nuts 406 acting to hold the spring 404 under compression. To actuate the thread tension and lock shaft 398 its extreme rearward end is connected to mechanism best shown in Figs. 3, 23 and 24. The rearward end of the lock shaft is threaded into a transverse pin 408 and is held from rotation in the pin by a check nut 410. The pin 408 is rotatable in a forked lever 312 fulcrumed on a stud 414 secured in the machine frame. A horizontal rearwardly extending arm of the lever 412 has a lengthwise passage at the end of which is a socket to receive the upper ball headed end of a link 416 held in place by a spring 418 within the passage of the lever arm, the spring being compressed between the fulcrum pin 414 and the ball head of the link 416. The lower end of the link 416 is pivotally connected by a pin 420 to a generally H-shaped cam arm 422 fulcrumed in turn on an adjusting lever 424.

The mechanism for actuating the thread tension and lock comprises a roll 426 at the rearward end of the pin 420 engaging an open cam 428 on the main sewing shaft. The cam 428 consists of a disc disposed between the cranks 80 and 82 providing a reinforcement and a strengthening member for the main sewing shaft between the cranks. The cam 428 rotates in the direction of the arrow on the cam shown in Figs. 3 and 23, the resistance caused by friction between the cam and the roll 426 tending to move the roll in the same direction when the cam arm is free to swing.

The thread tension and lock mechanism is adjustable to change the timing of lock actuation with relation to the rotation of the cam on the sewing shaft. For this purpose, the cam arm 422 of the thread tension and lock actuating mechanism is arranged for swinging movement with the adjusting lever 424. The adjusting lever 424 is offset and provided with an elongated hub. At the forward end of the hub of lever 424 is a forked downwardly extending arm having a pivot 430 secured therein on which the cam arm 422 is pivotally mounted. An upwardly extending arm of the adjusting lever 424 has formed thereon an integral pin portion surrounded by an eye at the enlarged end of an adjusting link 432. The adjusting link passes through an opening in the right side of the machine frame 32 (see Figs. 1, 2 and 23) and is threaded to receive an adjusting thumb nut 434 disposed outside the machine frame at a convenient location for easy rotation. To retard the time of operation of the thread lock, rotation of the thumb nut 434 to tighten the nut actuates the adjusting lever to impart a swinging movement to the cam roll 426 in a direction opposite the movement of the outer surface on the cam 428. The frictional resistance thus offered by the cam roll tends to hold the

adjusting link and lever at the limits of their adjusting movement. To accelerate the time of operation of the thread lock, the thumb nut is loosened and the adjusting lever is freed for swinging movement with the cam arm 422 in the same direction as the cam movement and the link 432 is surrounded by a coil spring 436 acting between the enlarged eye end of the link and the inner surface of the machine frame. If there is for any reason an unusual resistance offered to relative movement between the cam 428 and the roll 426, this resistance will not effect the adjustment or tend to compress the spring 436, the spring acting to move the adjusting lever always in the direction of cam movement and not against it. To limit free movement of the adjusting lever by the spring 436, a downward projection therefrom is notched to receive a fixed pin 437 (see Fig. 3) secured in the frame of the machine.

The operation of the machine will be more clearly understood with reference to Fig. 25 of the drawings. As indicated therein, the awl acts to penetrate the work during the first part of each sewing cycle. This occurs while the work is clamped between the stationary guide foot and the work support, the relative position of the work being shown by the shaded area. The needle is then projected upwardly through the awl perforation in closed spaced relation to the awl as it withdraws, so that no chance of work displacement occurs during the transfer of the needle to the awl perforation. The take-up takes up the thread at a time when the work is clamped between the upper and lower feed feet. Each stitch actually is set after the feed takes place and the work is clamped by the guide foot and work support, the awl starting to enter the work at about the same time. In this way, there is no opportunity for gripping the thread between the work and the work support while the take-up is contracting each loop of thread from its state of maximum extension substantially to the surface of the work, with the result that a uniformly reliable loop contraction is provided.

The thread is controlled with certainty during formation of each stitch by the thread lock which is closed, particularly while the take-up is giving up thread to the shuttle. The thread lock is released after each needle loop is drawn to the surface of the work before each stitch is set, providing only an effective tension while the take-up is drawing an amount of thread from the supply determined by the thickness of the work. The thread lock is closed after the thread is drawn from the supply. As soon as the thread lock comes on, gripping the thread, the needle loop with locking thread is drawn a uniform distance into the work to set the stitch. Regulation of the time at which the thread lock comes on is adjustable through the time range indicated by the solid and dot-dash lines and the rotation "Off-On" of the thread lock curve in Fig. 25. This lock application time occurs nearly at the final end of the taking up stroke of the take-up.

For controlling the running of the machine the main sewing shaft carries a driving and stopping mechanism including a slideable clutch member 438 splined on the shaft and having secured to its hub a bearing 440 engaged by a pair of diametrically opposed pins 442 in a yoke 444. The yoke 444 comprises a lever fulcrumed on a fixed rod 446 and has a horizontal arm carrying a pin 448. The pin 448 is engaged by the lower end of a tension spring 450, the upper end of

which is hooked over a stud 452 threaded into the machine frame. The spring 450 causes the clutch member 438 to be drawn into frictional engagement with a circular brake disc 454 secured within a recess of the frame surrounding the shaft 84. When the clutch member is drawn against the disc a braking action is effected causing the main sewing shaft to be brought promptly to rest.

- 10 To actuate the clutch member 438 away from the brake disc 454 and to cause the sewing shaft to be rotated, the pin 448 has connected to it a treadle rod 456 extending downwardly to a conveniently located treadle (not shown) at the base 15 of the machine. Depression of the treadle rod moves the clutch member 438 away from the disc 454 and into engagement with a rotating driving clutch member 458 loosely mounted on the end of the shaft and having secured to its hub a friction reducing bearing 460 disposed between the hub of the driving member and a cover plate 462 enclosing the recess containing the disc 454 in the frame of the machine. The bearing 460 thus assists in supporting the outer end of the 20 main sewing shaft. To rotate the driving clutch member 458 its hub has secured to it a pulley 464 driven by a belt extending to a suitable source of power (also not shown). The extreme outer end of the shaft has pinned to it a hand wheel 25 466 for bringing the sewing shaft to a convenient 30 stopping position if required.

To assist in releasing and replacing the work in the machine, the work support is connected to a second foot treadle, not shown, which when 35 depressed lowers the work support from the guide foot 18. To this end the rearward end of the shaft 42 has pinned to it a horizontal arm 468 (see Fig. 4). Pivoted connected to the arm is a 40 downwardly extending treadle rod 470 connecting the arm with the work support lowering treadle.

For convenience in removing a locking thread supply bobbin from the thread case 202, the hollow shaft 196 has slidably mounted within it a vertical pin 472, the upper end of which is guided 45 in alignment with an opening in the bottom of the thread case (see Figs. 1, 2 and 3). The lower end of the pin has an enlarged perforated head for receiving a pin 474 passing through an H-shaped link 476. The link 476 also carries a pin 50 478 forming a pivotal connection with a finger lever 480 fulcrumed in the machine frame and projecting through the right side thereof. Downward movement of the projecting arm of the finger lever 480 raises the pin 472 and ejects the 55 locking thread supply bobbin. To hold the ejector pin 472 in lowered inoperative position, the pin 478 has stretched between it and a fixed stud 492 a tension spring 484.

60 The nature and scope of the invention having been indicated and a specific embodiment having been described what is claimed is:

1. A sewing machine having a needle, a guide foot, a work support and a vertical guideway 65 along which the work support is movable toward and from the guide foot, in combination with a pair of feed feet at opposite sides of a location ordinarily occupied by the work, and means for actuating the feed feet to clamp and feed the work, one of said feet being connected to the work support by a floating actuating lever to cause the work support to be lowered from engagement with the work during feeding movement of the feed feet.

70 2. A sewing machine having a needle, a guide

foot, a work support and a vertical guideway along which the work support is movable toward and from the guide foot, in combination with a feed foot connected to the work support by a floating actuating lever to cause the work support to be lowered from engagement with the work during feeding movement of the feed foot and mechanism for actuating the feed foot for causing the feed foot to clamp the work comprising a vertically sliding connection with the floating lever.

3. A sewing machine having a needle, a guide foot, a work support and a vertical guideway along which the work support is movable toward and from the guide foot, in combination with a pair of feed feet at opposite sides of a location ordinarily occupied by the work, means for actuating the feed feet to clamp and feed the work, one of said feet being connected to the work support by a floating actuating lever to cause the work support to be lowered from engagement with the work during feeding movement of the feed feet and mechanisms for actuating feed feet in the direction of feed comprising a rotating varying speed-ratio drive.

4. A sewing machine having a needle, a guide foot, a work support and a vertical guideway along which the work support is movable toward and from the guide foot, in combination with a pair of feed feet at opposite sides of a location normally occupied by the work, both of which are actuated to clamp and feed the work, connections including a floating lever between the work support and one of said feed feet to cause the work support to be lowered from engagement with the work during feeding movement of the feed feet, and mechanisms for actuating the feed feet in the direction of feed comprising a rotating varying speed-ratio drive and a single vertical lever connecting the two feed feet.

5. A sewing machine having a needle, a guide foot, a work support and a vertical guideway along which the work support is movable toward and from the guide foot, in combination with a pair of feed feet at opposite sides of a location normally occupied by the work, both of which are actuated to clamp and feed the work, connections including a floating lever between the work support and one of said feed feet to cause the work support to be lowered from engagement with the work during feeding movement of the feed feet, and mechanisms for actuating the feed feet in the direction of feed comprising a rotating varying speed-ratio drive, a single vertical lever connecting the two feed feet and a motion reversing connection between the end of the connecting lever and one of the feed feet to cause both feet to move along the line of feed in the same direction.

6. A sewing machine having a needle, a guide foot, a work support and a vertical guideway along which the work support is movable toward and from the guide foot, in combination with a pair of feed feet at opposite sides of a location normally occupied by the work, both of which are actuated to clamp and feed the work connections including a floating lever between the work support and one of said feed feet to cause the work support to be lowered from engagement with the work during feeding movement of the feed feet, and mechanisms for actuating the feed feet in the direction of feed comprising a rotating varying speed-ratio drive, a single vertical lever connecting the two feed feet and an adjustable throw connection for actuating the connecting lever.

7. A sewing machine having a hook needle, an awl, and other stitch forming devices, a main sewing shaft for actuating the stitch forming devices, in combination with link motions connected to the needle and awl, each motion including a crank and pitman driven from the main sewing shaft and the awl link motion being driven through a camless varying speed-ratio device connected between the awl link motion and the main sewing shaft.

8. A sewing machine having a hook needle, an awl, and other stitch forming devices, a main sewing shaft for actuating the stitch forming devices, in combination with a compound time-changing linkage for actuating the needle from the main sewing shaft, a camless rotating varying speed-ratio device driven by the main shaft, and a compound timing-changing linkage driven by said device for actuating the awl.

20 9. A sewing machine having a hook needle, an awl, and other stitch forming devices, a main sewing shaft for actuating the stitch forming devices, in combination with a link motion for actuating the needle from the main sewing shaft and a loop picker actuated by the needle actuating link motion to engage each loop carried by the needle.

10 10. A sewing machine having a sewing shaft, a hook needle, a needle looper, a guide foot, and a work support, in combination with a feed foot connected to the work support, and mechanism for actuating the feed foot in the direction of feed comprising a member rotating twice for each single rotation of the sewing shaft, and a rotating varying speed-ratio drive on said member and a member driven a single rotation for each two rotations of the varying speed-ratio drive connected between said drive and the feed foot to cause quick feeding and back-feeding movements with relatively slow movements between the quick movements thereof.

15 11. A sewing machine having a sewing shaft, a hook needle, a needle looper, a guide foot, and a work support, in combination with a feed foot connected to the work support, mechanism for actuating the feed foot in the direction of feed comprising a member rotating twice for each single rotation of the sewing shaft, and a rotating varying speed-ratio drive on said member and a member driven a single rotation for each two rotations of the varying speed-ratio drive connected between said drive and the feed foot to cause quick feeding and back-feeding movements with relatively slow movements between the quick movements thereof, and mechanism driven from the sewing shaft for actuating the feed foot to clamp and release the work.

20 12. A sewing machine having a sewing shaft, a hook needle, a needle looper, a guide foot, and a work support, in combination with a feed foot connected to the work support, mechanism for actuating the feed foot in the direction of feed comprising a member rotating twice for each single rotation of the sewing shaft, and a rotating varying speed-ratio drive on said member and a member driven a single rotation for each two rotations of the varying speed-ratio drive connected between said drive and the feed foot to cause quick feeding and back-feeding movements with relatively slow movements between the quick movements thereof, and a second feed foot at the opposite side of the work from the first-mentioned feed foot acting in unison therewith to clamp and feed the work.

25 13. A sewing machine having a sewing shaft, a hook needle, a needle looper, a guide foot, and

a work support, in combination with a feed foot connected to the work support, mechanism for actuating the feed foot in the direction of feed comprising a member rotating twice for each single rotation of the sewing shaft, and a rotating varying speed-ratio drive on said member and a member driven a single rotation for each two rotations of the varying speed-ratio drive connected between said drive and the feed foot to cause quick feeding and back-feeding movements with relatively slow movements between the quick movements thereof, and a loop taken driven two rotations from the two-rotation member for each single rotation of the sewing shaft.

14. A sewing machine having a sewing shaft and work penetrating devices including a needle and an awl, in combination with mechanism for actuating the work penetrating devices, comprising a constant speed rotating member driven by the sewing shaft for one of said devices and a rotating varying speed-ratio drive driven from the sewing shaft having a crank and compound timing changing connections between the crank and the other of said devices.

15. A sewing machine having a sewing shaft and work penetrating devices including a needle and an awl, in combination with mechanisms for actuating the needle and awl, comprising a constant speed rotating member driven by the sewing shaft for the needle and a rotating varying speed-ratio drive driven from the sewing shaft having a crank and compound timing-changing connections between the crank and the awl.

16. A sewing machine having a sewing shaft and work penetrating devices including a needle and an awl, in combination with mechanism for actuating the work penetrating devices, comprising a constant speed rotating member driven by the sewing shaft for one of said devices and a rotating varying speed-ratio drive driven from the sewing shaft having a crank and compound timing-changing connections between the crank and the other of said devices, said compound timing-changing connections having a pivotal joint beyond the crank arranged to reverse the motion of the latter of said devices during continued movement of other of the timing-changing connections in one direction.

17. A sewing machine having a sewing shaft, a needle and an awl, in combination with mechanism for actuating the awl, comprising a rotating varying speed-ratio drive driven from the sewing shaft, having a crank, a pitman for the crank and a compound timing changing connection between the pitman and the awl, said compound timing-changing connections having pivots beyond the pitman arranged to reverse the motion of the awl during continued movement of the pitman in one direction.

18. A sewing machine having a sewing crank shaft, a needle and an awl, in combination with mechanisms for actuating the needle and awl, comprising a compound timing-changing link connection driven by a crank on the sewing shaft for the needle, rotating varying speed-ratio drive driven from the sewing shaft, a crank driven by the rotating varying speed-ratio drive, and a compound timing-changing link connection between the crank and the awl.

19. A sewing machine having a needle, a guide foot, a work support, and a vertical guideway along which the work support is movable toward and from the guide foot, in combination with a feed foot connected to the work support by a floating actuating lever to cause the work sup-

port to be lowered from engagement with the work during feeding movement of the feed foot.

5 20. A sewing machine having a main sewing shaft, actuating mechanism driven therefrom, a hook needle and an awl mounted and actuated to form a perforation in the work for the needle, in combination with a rotary looper for laying thread in the hook of the needle provided with a guiding opening through which the awl passes, said needle and looper being actuated by said mechanisms to cause the needle to enter into the awl guiding opening during the looping operation.

15 21. A sewing machine having a main sewing shaft, actuating mechanism driven therefrom, a hook needle and an awl mounted and actuated to form a perforation in the work for the needle operating at opposite sides of a location normally occupied by the work, in combination with a rotary looper provided with an awl guiding opening concentric to its axis of rotation, said needle and looper being actuated by said mechanism to cause the needle to enter into the awl guiding opening during the looping operation.

20 22. A sewing machine having a main sewing shaft, actuating mechanism driven therefrom, a hook needle, an awl mounted and actuated to form a perforation in the work for the needle, and a shuttle mounted and actuated by said mechanism to enter each loop of thread passed through the work by the needle, in combination with a rotary needle looper provided with an awl guiding opening through which the awl reciprocates toward and from the work, said needle and looper being actuated by said mechanism to cause the needle to enter the awl guiding opening during the looping operation, and said looper being mounted at the side of a location normally occupied by the work opposite the shuttle.

25 30 40 23. A sewing machine having a hook needle and an awl, in combination with a rotary needle looper provided with an awl guiding opening into which the needle enters during the looping operation and a rotary thread measuring finger acting on the needle thread between the looper and the work, the axis of rotation of which finger is disposed at an angle to the rotary axis of the looper.

35 45 50 55 24. A sewing machine having a hook needle, an awl, a rotary needle looper, and a rotary thread measuring finger acting on the needle thread between the looper and the work, in combination with a work engaging guide foot having a thread engaging surface along which the rotary thread measuring finger moves during each sewing cycle to cause a length of thread to be pressed against the guide foot.

60 65 25. A sewing machine having a hook needle, an awl, a needle looper and a rotary thread measuring finger formed with an arcuate thread engaging flange acting on the needle thread between the looper and the work, in combination with a concave member within the concavity of which the arcuate flange of the thread finger moves to cause a uniform length of thread to be measured between the arcuate flange and the concave member.

70 75 26. A sewing machine having a hook needle and an awl at opposite sides of the work, in combination with a rotary needle looper provided with an eccentric thread guiding opening and an awl guiding opening concentric to its axis of rotation into which the needle enters during the looping operation and a rotary thread measuring finger formed with an arcuate thread engaging

flange projecting into the path of the thread carried by the looper and stretched between the looper and the work while the thread is at one side of the needle to enable the thread to be engaged by the thread finger without interfering with the needle.

27. A sewing machine having a hook needle, an awl and a needle looper, in combination with a rotary thread measuring finger formed with an arcuate thread engaging flange notched at one end and disposed to project into the path of the thread carried by the looper at one side of the needle between the looper and the work to enable the thread to be engaged with the notch without interfering with the needle, and mechanism for actuating the thread finger in the direction of work feed to measure thread and in the opposite direction to release the measured thread while the needle is retracting from the work.

28. A sewing machine having a hook needle, an awl, a rotary needle looper, and a rotary thread finger, in combination with a guide foot having a thread engaging surface cooperating with the thread finger to cause a uniform length of thread between the looper and the work to be measured between the guide foot and the thread finger, the thread engaging surface on the guide foot being grooved to cooperate with the thread finger in trapping the thread between them.

29. A sewing machine having a hook needle, an awl, a needle looper, and a rotary thread measuring finger formed with an arcuate thread engaging flange and arranged to act on the thread between the looper and the work, in combination with a grooved concave member within the concavity of which the arcuate flange on the thread finger moves to cause a uniform measured length of thread to be trapped within the groove of the concave member by the arcuate flange.

30. A shoe sewing machine having a hook needle and a rotary looper provided with an opening to receive the needle, in combination with a rotary thread measuring finger acting on the thread between the looper and the work, the axis of rotation of which thread finger is disposed at an angle to the rotary axis of the looper.

31. A shoe sewing machine having a sewing shaft, a hook needle and a rotary looper provided with an opening to receive the needle, in combination with a rotary thread measuring finger acting on the thread between the looper and the work, the axis of rotation of which thread finger is disposed at an angle to the rotary axis of the looper and mechanisms for actuating the looper and thread finger comprising separate cranks on the sewing shaft and link connections between the cranks, and the looper and thread finger.

32. A shoe sewing machine having a sewing shaft, a hook needle and a rotary looper provided with an opening to receive the needle, in combination with a rotary thread measuring finger acting on the thread between the looper and the work, the axis of rotation of which thread finger is disposed at an angle to the rotary axis of the looper, and mechanisms for actuating the looper and thread finger comprising separate cranks of substantially equal throw located on the sewing shaft with approximately 180° displacement and link connections between the cranks, and the looper and thread finger.

33. A shoe sewing machine having stitch forming devices including a hook needle and a rotary loop taker formed with a loop entering beak, in combination with a loop picker mounted at one side of the needle to enter each needle loop and

to assist in transferring each needle loop to the loop taker beak and provided with a loop entering end pointed in the same direction as the loop taken beak during transfer of the needle loop thereto.

34. A shoe sewing machine having stitch forming devices including a hook needle and a rotary loop taker formed with a loop entering beak, in combination with a loop picker mounted on a

10 stud located along the line of the seam inserted by the stitch forming devices beyond the needle to enter each needle loop and provided with a loop entering end pointed in the direction of movement of the loop taker adjacent to the loop picker during transfer of the needle loop thereto.

35. A shoe sewing machine having work feeding means and stitch forming devices including a hook needle and a loop taker rotating about an axis at 90° to the plane of the work operated upon, in combination with a loop picker acting to enter each needle loop and having a loop entering end pointed against the direction of work feed for assisting in transferring each needle loop to the loop taker.

20 36. A shoe sewing machine having work feeding means and stitch forming devices including a hook needle and a loop taker rotating about an axis at 90° to the plane of the work operated upon, in combination with a loop picker acting

25 to enter each needle loop and having a loop entering end pointed against the direction of work feed for assisting in transferring each needle loop to the loop taker, the open hook of the needle also facing against the direction of work feed and the loop taker having a loop entering beak directed similarly during transfer of the needle loop thereto.

37. A sewing machine having a sewing shaft, a hook needle, a thread lock and a cam on the sewing shaft for actuating the thread lock, in combination with mechanism for actuating the thread lock comprising a cam arm and an adjusting lever on which the cam arm is pivoted arranged to impart swinging movement to the cam arm in the direction of cam movement when the adjusting lever is free to swing about its fulcrum, an adjusting link connected to the adjusting lever and an adjusting nut threaded on the adjusting link for swinging the adjusting lever in a direction to move the cam arm opposite to the movement of the cam to change the timing of the thread lock with relation to the rotation of the sewing shaft.

38. A sewing machine having a sewing shaft, a hook needle, a thread lock and a cam on the sewing shaft for actuating the thread lock, in combination with mechanism for actuating the thread lock comprising a cam arm and an adjusting lever on which the cam arm is pivotally

50 arranged to impart swinging movement to the cam arm in the direction of cam movement when the adjusting lever is free to swing about its fulcrum, an adjusting link connected to the adjusting lever, an adjusting nut threaded on the adjusting link for swinging the adjusting lever in a direction to move the cam arm opposite to the movement of the cam to change the timing of the thread lock with relation to the rotation of the sewing shaft, and a spring carried by the adjusting link for actuating the adjusting lever to

65 move the cam arm in the direction of cam movement when the adjusting screw is unscrewed to free the adjusting lever.

70 39. A sewing machine having a hook needle, an

awl, a rotary needle looper and a rotary thread measuring finger acting on the needle thread between the looper and the work, in combination with a thread engaging member having a surface along which the rotary thread measuring finger moves during each sewing cycle to cause a length of thread extending between the looper and the work to be pressed against said member.
